Specification for Design.

Patented June 20, 1922.

Application filed April 8, 1922. Serial No. 1,639. Term of patent 7 years.

To all whom it may concern:

Be it known that I, FREDERICK ROETTGES, a citizen of the German Republic, residing at Stamford, county of Fairfield, and State of Connecticut, have invented a new, original, and ornamental Design for a Lamp Shade, of which the following is a specification, reference being had to the accompanying drawing, forming part thereof.

Fig. 1 of the drawing is a perspective view of a lamp having a shade according to my design. All parts not comprised in my invention are shown in dotted lines.

Fig. 2 is a top plan view of my shade.

I claim:

The ornamental design for a lamp shade as shown.

In testimony whereof, I have signed my name to this specification in the presence of two subscribing witnesses, this fifteenth day of March, 1922.

FREDERICK ROETTGES.
